SPANNER WRENCH

Herbert L. Fish, Falls Church, Va., assignor to Pendleton
Tool Industries, Inc., Los Angeles, Calif., a corporation
of California

Filed Aug. 14, 1962, Ser. No. 71,289

Term of patent 14 years

(Cl. D54—16)

FIG. 1 is a perspective view of a spanner wrench showing my new design;

FIG. 2 is a side elevation thereof;

FIG. 3 is a top plan view thereof;

FIG. 4 is an edge elevation, as viewed from the left as seen in the aspect of FIG. 2; and

FIG. 5 is a bottom plan thereof.

I claim:

The ornamental design for a spanner wrench, substantially as shown.
